RECOIL PAD FOR GUNS

Frank Pachmayr, Los Angeles, Calif., assignor,
by mesne assignments, to Fray-Mershon, Inc.,
Los Angeles, Calif., a corporation of California

Application January 28, 1935, Serial No. 3,777

9 Claims. (Cl. 42—74)

This invention relates to and has for an object the provision of a substantially resilient cushion, or pad for attachment to the end of a gun stock and adapted to rest against the shoulder of a marksman for cushioning the body of the marksman against the impact resulting from firing a gun.

My invention contemplates the provision of an elongated body formed of soft rubber mounted upon a base of hard rubber or other material, the body being formed with solid end portions of substantial thickness and the intermediate portion of the body being of cellular form with a plurality of tubular ribs extending transversely and open throughout their length and connected at their end to the outer and inner walls of the body by means of short ribs. Said tubular ribs are also connected by ribs extending therebetween and are of elliptical cross section with their major axes disposed at right angles to the outer and inner walls of the body, thereby providing between said tubular ribs, said walls and said ribs, inner and outer rows of cells which latter, as well as the tubular ribs, are collapsible. Thus, the tubular ribs are readily collapsible when pressure is applied to the upper wall of the body, as when a gun is fired, thereby absorbing the shock resulting from the explosion, and are yet of sufficient rigidity to withstand the normal pressure of the gun against the body of a marksman without collapsing to an appreciable extent.

Another object is to provide a recoil pad for guns having a ribbed outer surface formed on the soft rubber body whereby the pad may be held against slippage against the shoulder of a marksman.

A still further object is to provide a gun pad formed with a cellular body of soft rubber superposed upon and secured to a sheet of rubber of the same or harder quality and preferably of a distinguishing color, and a base of hard rubber or other material underlying the sheet of rubber for stiffening the body against bending at points intermediate its ends.

Other objects may appear as the description progresses.

I have shown a preferred form of my invention in the accompanying drawing, subject to modification within the scope of the appended claims without departing from the spirit of my invention.

In said drawing:

Fig. 1 is an external side view of my recoil

pad attached to the end of a gun stock for use;

Fig. 2 is a top plan view of the pad;

Fig. 3 is a sectional plan of the same on line 3—3 of Fig. 1;

Figs. 4 and 5 are, respectively, transverse sections of the pad on lines 4—4 and 5—5 of Fig. 1.

In its preferred form the pad is formed with an elongated soft rubber body 1 having solid ends 2 and 3 and intermediate cellular portions formed with thin outer and inner walls 4 and 5, a longitudinally arranged series of aligned tubular partitions 6, 6, etc. of elliptical cross section, short ribs or webs 7, 7, etc. connecting the outer portions of the partitions 6 with the outer wall 4, similar ribs or webs 8, 8, etc. connecting the inner portions of said partitions with the inner wall 5, and short ribs or webs 9, 9, etc. arranged between and connecting adjacent portions of the partitions, as shown in Fig. 1.

A flat thin sheet 10 of rubber of a grade and color different from the body 1 is vulcanized to the inner wall 5, and a base of stiff hard rubber 11 is vulcanized to the lower sides of the sheet 10, so as to form a composite pad incapable of bending longitudinally but capable of depression and collapse at points intermediate the solid end portions 2 and 3.

The outer surface of the pad is suitably ribbed, as shown in Fig. 2, at 12, either longitudinally or transversely, or otherwise, for providing a gripping surface for contact with the shoulder of a marksman and thereby preventing slippage of the gun and consequent inaccuracy in shooting.

At opposite ends of the series of tubular partitions 6 I provide arcuate cells 13, 13 which conform to the curvature of the adjacent portions of the endmost partitions 6, 6 and permit the outward distension of said endmost partitions. The form of the partitions 6 and the ribs 7, 8 and 9 provide inner and outer rows of cells 14, 14, etc. which extend between the tubular ribs and the inner and outer walls of the pad.

The form and arrangement of the partitions, ribs and cells is most important for the reason that sufficient yieldability at local points is desirable in a pad of the character shown and described, without unnecessary distortion or general collapse of the body 1. Yet the pad must be sufficiently stiff and unyielding as to permit the firm adjustment of a gun to the body of a marksman. Moreover, the elliptical form of the partitions 6, connected as they are with the outer and inner walls of the body and with each other, permit a more ready collapse and distortion of the partitions than is possible with circular or

other forms of partitions, for the reason that when pressure is applied to the outer wall 4 the partitions 6 flatten out and incline themselves at angles of 45 degrees or less, depending upon the amount of pressure applied, and nest snugly together at such angles. The end cells 13 contribute to the aforesaid result by approaching a semi-circular cross sectional form so that the walls of the adjacent partitions 6 may spread laterally into the concavities of said cells 13.

When pressure is applied at points on the outer wall of the pad opposite the endmost partitions 6 the partitions at the two ends will incline in opposite directions, while the application of pressure at an intermediate point will cause the inclination of the partitions in either one or the other direction according to the extent and directness or indirectness of the line of pressure.

It will be understood that by extending the partitions 6 and the ribs 7, 8 and 9 entirely through the body 1 without intersecting partitions or ribs, the pad is rendered uniformly yieldable and resilient throughout the cellular area, whereas such partitions or ribs would tend to stiffen the pad at the points of intersection. Obviously, the solid end portions 2 and 3 while yieldable because of the inherent resiliency of the material of which the body is formed, are substantially less yieldable than the intermediate portions of the pad.

The provision of the sheet 10 between the body 1 and base 11, when formed of less yieldable material than the body 1 and of a different color and grade, serves as a bond between the body and the base and lends distinction to the pad.

As shown in Figs. 2 and 3, apertures 15, 15, may be formed in the body 1, sheet 2 and base 3, for the insertion of screws by means of which the pad is detachably held on the end of a gun stock G.

As shown in Figs. 1 and 3, I may provide a series of posts 16, 16, etc. in a row intermediate the sides of the pad and connecting the walls 4 and 5 with the horizontal ribs 9, for stiffening the pad in the center.

The ribs 12 are preferably of saw tooth form so as to provide firm grips and may be longitudinal or transverse, or both as shown.

50 It should be noted that the tubular members 6 are in line and equi-distantly spaced from one another and from the inner and outer walls of the pad. The cells or openings 13 of the inner row are directly opposite the corresponding cells 55 or openings 13 of the outer rows, said cells being between said tubular members. Thus, the tubular members 6 are located centrally of the walls 4 and 5 are therefore free to collapse, with the walls thereof extended against the outer 60 and inner walls 4 and 5, such extension of the walls of said tubular members being made possible by the rows of cells 13. This arrangement provides the desired rigidity while, at the same time, permitting of a ready and positive shock 65 absorber action.

Thus, the body of the pad may be said to be characterized by three vertical rows of transversely extending and spaced openings which define the central row of independently collapsible tubular members, the outermost rows permitting distention of the walls of said members when the same are collapsed.

What I claim is:

1. In a recoil pad for gun stocks, an elongated body formed of soft rubber and having solid end

portions, a cellular portion between said end portions, inner and outer walls, said cellular portion including spaced and independently collapsible tubular members arranged between and spaced from said inner and outer walls and said end portions, and web portions joining said tubular members with one another and with said inner and outer walls.

2. In a recoil pad for gun stocks, an elongated body formed of soft rubber and having solid end portions, a cellular portion between said end portions, inner and outer walls, said cellular portion including spaced and independently collapsible tubular members arranged between and spaced from said inner and outer walls and said end portions, and web portions joining said tubular members with one another and with said inner and outer walls, said tubular members being alined in a straight row and equi-distantly spaced from said walls.

3. In a recoil pad for gun stocks, an elongated body formed of soft rubber and having solid end portions, a cellular portion between said end portions, inner and outer walls, said cellular portion including spaced and independently collapsible tubular members arranged between and spaced from said inner and outer walls and said end portions, and web portions joining said tubular members with one another and with said inner and outer walls, said tubular members having their major axes at right angles to the longitudinal axes of said walls.

4. In a recoil pad for gun stocks, an elongated body formed of soft rubber and having solid end portions, a cellular portion between said end portions, inner and outer walls, said cellular portion including spaced and independently collapsible tubular members arranged between and spaced from said inner and outer walls and said end portions, and web portions joining said tubular members with one another and with said inner and outer walls, said tubular members and webs extending transversely of and between said walls, the portions of those of the tubular members which are opposed to said solid end portions being spaced throughout from said end portions.

5. In a recoil pad for gun stocks, an elongated body formed of soft rubber and having solid end portions, a cellular portion between said end portions, inner and outer walls, said cellular portion including spaced and independently collapsible tubular members arranged between and spaced from said inner and outer walls and said end portions, and web portions joining said tubular members with one another and with said inner and outer walls, said tubular members, webs and said walls defining between the walls and said row of tubular members inner and outer rows of openings into which latter the tubular members are extensible when collapsed.

6. In a recoil pad for gun stocks comprising a soft rubber inner wall, a soft rubber outer wall, end portions joining said wall, a plurality of independently collapsible tubular members disposed between said walls, and web portions extending between and joining said tubular portions and being substantially parallel with said walls.

7. In a recoil pad for gun stocks comprising a soft rubber inner wall, a soft rubber outer wall, end portions joining said wall, a plurality of independently collapsible tubular members disposed between said walls, web portions extending between and joining said tubular portions and being substantially parallel with said walls, and

other web portions extending between each of said tubular members at right angles to the first named webs and joining said members to said walls.

5. 8. In a recoil pad for gun stocks comprising a soft rubber inner wall, a soft rubber outer wall, end portions joining said wall, a plurality of independently collapsible tubular members disposed between said walls, web portions extending between and joining said tubular portions and being substantially parallel with said walls, and other web portions extending between each of said tubular member at right angles to the first named webs and joining said members

to said walls, said walls, webs and tubular members defining between the tubular member and said walls inner and outer rows of openings permitting collapse of said tubular members.

9. In a recoil pad for gun stocks comprising a soft rubber inner wall, a soft rubber outer wall, end portions joining said wall, a plurality of independently collapsible tubular members disposed between said walls, and web portions extending between and joining said tubular portions and being substantially parallel with said walls, said tubular members being substantially oval in cross section. 5 10
